UNITED STATES PATENT OFFICE

OSCAR CHARLES ROESSEN, OF BROOKLYN, NEW YORK, ASSIGNOR TO WOOD NEWSPAPER MACHINERY CORPORATION, OF NEW YORK, N. Y., A CORPORATION OF VIRGINIA.

PARALLEL ADJUSTMENT FOR FOLDING COUPLES

Application filed June 27, 1928, Serial No. 288,613. Renewed April 29, 1931.

The principal object of this invention is to provide means whereby the two journals of one of the cylinders constituting a folding couple for a paper folding machine can be adjusted equally and are necessarily so adjusted. Another object is to provide a construction for performing this adjustment in which the amount of the adjustment can be read easily on a scale, thus eliminating the hand method of adjustment now employed individually at each end of the cutting cylinder and avoiding the necessity of measuring the distance between the two cylinders for different sizes of the folded product.

Other objects and advantages of the invention will appear hereinafter.

Reference is to be had to the accompanying drawings in which

Fig. 1 is a plan of a folding couple showing a preferred form of this invention;

Fig. 2 is an end view of the same;

Fig. 3 is a sectional view on the line 3—3 of Fig. 2;

Fig. 4 is a plan of a modification;

Fig. 5 is an end view thereof;

Fig. 6 is a plan of a third form, and

Fig. 7 is an end view of the same.

In the form shown in Figs. 1, 2 and 3, the folding cylinder 10 is of the usual construction, cooperating with the folding rolls 11 and having folding blades 12. The cutting cylinder 13 cooperates with the folding cylinder as usual.

It will be obvious that when various sizes of newspapers are run through the folder, the space between the folding and cutting cylinders has to be altered. It is considerably less for a sixteen page paper for example than for a sixty-four page paper.

One of the cylinders, preferably the cutting cylinder, is mounted on pillow blocks 14. It is the ordinary procedure to move the pillow blocks at each end supporting the journals of the cutting cylinder in order to secure the desired adjustment. The pressman has to adjust each pillow block independently and has to measure the space between the cylinders 10 and 13 by gauges or feelers to ascertain when he has the right adjustment. Then he has to tighten up bolts

on each end and be careful that the adjustment is not lost while doing it. It is only by the use of the gauges or feelers at each end that he can be sure that the two cylinders are left in parallel condition.

In the form shown in Figs. 1, 2 and 3, the journals or studs of the cutting cylinder are mounted in eccentric boxes 17 which constitute movable supports for the cutting cylinder. Obviously these boxes will move the journals. The fact that they may raise the journals or lower them a little is not important in this kind of a machine. These eccentric boxes are originally set alike and each one is equipped with a segmental worm wheel 18. These two worm wheels are operated by segmental worms 19 located on parallel shafts 20 arranged in suitable bearings and each one provided with a worm wheel 21 and one of them with a circular graduated dial 22 which cooperates with a zero point 23 on the bearing in stationary position.

The two worm wheels 21 mesh with two worms 24 on an operating shaft 25 having a hand wheel 26. Obviously the turning of the hand wheel 26 will adjust both bearings in the same manner and to the same degree and the amount will be indicated on the dial 22.

In the form shown in Figs. 4 and 5, the method is quite similar, the pillow blocks are employed in the same way, but they are themselves adjustable, constituting movable supports. They are provided with slots 15 wide enough to allow for the adjustment of the blocks in spite of the holding bolts 16. Each one is held in place by an adjusting screw 30, these two screws being parallel. By gears 31 they are connected with an operating shaft 32 having a hand wheel 33 for operating it. This hand wheel itself is provided with a circular gauge or graduated area 34 and a stationary pointer 35 is mounted on the bearing. This constitutes simple means for accomplishing the same result as in Figs. 1, 2 and 3.

Referring now to Figs. 6 and 7, I have shown the sliding pillow blocks 14 of the same kind as being adjusted by a wedge 36 for each one. The two wedges are connected by

a threaded rod 37 which passes through both of them and has two screw threads of the same hand. This rod is provided with a pinion 38 meshing with a gear 39 equipped with a handle 40. The turning of this gear by the handle will turn the rod 37 and move the wedges in or out to adjust the two pillow blocks. The gear is provided with a dial 41 cooperating with a stationary pointer 42 for the purposes previously described. Another pair of wedges 43 are employed having a similar adjusting screw 44 for the purpose of jamming up the wedges 36 to eliminate all back-lash from the pillow blocks.

15 In all the forms shown, the same general result is secured, adjusting both supports simultaneously and equally, thereby maintaining parallelism between the cutting and folding cylinders and providing an indicator calibrated for the purpose of showing the space left between the cylinders.

Although I have illustrated and described only three forms of the invention, I am aware of the fact that other modifications can be 25 made therein by any person skilled in the art without departing from the scope of the invention as expressed in the claims. Therefore, I do not wish to be limited to all the details of construction herein shown and described, but what I do claim is:

30 1. The combination with a folding couple comprising a folding cylinder and a cutting cylinder, of movable supports at each end of one of said cylinders, and means for simultaneously moving the two end supports toward or from the other cylinder at equal speeds and a graduated dial operated by said last mentioned means for showing the adjustment.

35 2. The combination with a pair of cylinders and a pair of pillow blocks, of eccentric boxes carried by the pillow blocks for supporting the opposite ends of one of the cylinders, whereby the turning of said boxes will move the cylinder toward or from the other cylinder, and a shaft extending across the machine having means for simultaneously turning the two eccentric boxes.

40 3. The combination with a pair of cylinders and a pair of pillow blocks, of eccentric boxes carried by the pillow blocks for supporting the opposite ends of one of the cylinders, whereby the turning of said boxes will move the cylinder toward or from the other cylinder, a wheel segment connected with each of said boxes, a worm for operating each segment, a shaft on which each worm is mounted, said shafts being parallel with each other, and a shaft extending across the machine having means for simultaneously turning the first named shafts equal distances in the same time.

45 4. The combination with a folding couple comprising a folding cylinder and a cutting cylinder, of movable supports at each end of

one of said cylinders, means for simultaneously moving the two end supports toward or from the other cylinder at equal speeds, and means for measuring and indicating the distance between the cylinders.

5. The combination with a folding couple comprising a folding cylinder and a cutting cylinder, of two movable means for supporting the journals of the cutting cylinder, a shaft, means connected with said shaft for simultaneously and equally moving the two movable means toward or from the folding cylinder, and a graduated dial operated by said shaft for showing the adjustment.

6. The combination with a folding couple comprising a folding cylinder and a cutting cylinder, of a pair of pillow blocks movably mounted for supporting one of said cylinders, a shaft extending across the machine parallel with the axes of said cylinders, a handle for turning said shaft by hand, means at opposite ends of the shaft for moving the two pillow blocks simultaneously and equally to adjust the distance between the cylinders and keep their axes parallel and a graduated dial operated by said last mentioned means for showing the adjustment.

7. The combination with a folding couple comprising a folding cylinder and a cutting cylinder, of a pair of pillow blocks movably mounted for supporting said cutting cylinder, a shaft parallel with the axes of said cylinders, a handle for turning said shaft by hand, means at opposite ends of the shaft for moving the two pillow blocks simultaneously and equally to adjust the distance between the cylinders and keep their axes parallel, a rotary dial connected with the shaft and a stationary pointer for showing the exact adjustment.

8. The combination with a printing couple, of a pair of laterally adjustable pillow blocks for supporting the cutting cylinder thereof, transverse screws for adjusting said pillow blocks back and forth, a shaft extending across the machine, a hand wheel on the shaft for turning it, and means for rotating the two screws from the shaft simultaneously and equally.

9. The combination with a folding couple comprising a cutting cylinder and a folding cylinder and a pair of pillow blocks adjustably mounted for supporting the cutting cylinder, of a pair of wedges for moving the two pillow blocks, a shaft having screw-threaded connection with the two wedges, whereby when the shaft is turned the two wedges will move forward or back equal distances, and means for turning said shaft.

10. The combination with a folding couple comprising a cutting cylinder and a folding cylinder and a pair of pillow blocks adjustably mounted for supporting the cutting cylinder, of a pair of wedges for moving the two pillow blocks, a shaft extending across the

machine having screw threaded connection with the two wedges, whereby when the shaft is turned the two wedges will move forward or back equal distances, another pair of 5 wedges for backing up the first named wedges, the second shaft having screw threaded connection with the second pair of wedges and a hand wheel having a circular gauge thereon connected with the first shaft for indicating the adjustment.

10 In testimony whereof I have hereunto affixed my signature.

OSCAR CHARLES ROESEN.
